UNITED STATES PATENT OFFICE

95,099

DESIGN FOR A LIQUID CONTAINER OR SIMILAR ARTICLE

Raymond A. Weissenborn, Montclair, N. J.

Application November 15, 1934, Serial No. 54,019

Term of patent 7 years

To all whom it may concern:

Be it known that I, Raymond A. Weissenborn, a citizen of the United States of America, residing at Montclair, county of Essex, and State of New Jersey, have invented a new, original, and ornamental Design for a Liquid Container or Similar Article, of which the following is a specification, reference being had to the accompanying drawing, forming part thereof.

Figure 1 is a plan view of the container.

Figure 2 is a side elevation of the container.

I claim:

The ornamental design for a liquid container or similar article as shown.

RAYMOND A. WEISSENBORN.
